LATCH HANDLE

Ralph W. Kerr, Bowman, N. Dak.

Application June 30, 1942, Serial No. 449,046

1 Claim. (Cl. 292—167)

This invention relates to improvements in latch handles particularly adapted for application to the doors of aeroplanes and automobiles.

It is an object of the invention to provide a handle for operating door latches which is confined in a recess in the door when in an inoperative position so that it is substantially flush with the door surface.

The conventional door handles project beyond the surface of the door and frequently result in injury to persons falling against the same or damage to clothing catching on the handle and the present invention is designed to obviate these objections and also prevent forcible turning of the handle when the door is locked.

Another object of the invention resides in providing a handle of the above-mentioned character which is simple and durable in construction, reliable and efficient in operation, and inexpensive to manufacture.

Other objects and advantages of the invention will be apparent during the course of the following description.

In the accompanying drawing forming a part of this specification and in which like numerals are employed to designate like parts throughout the same,

Fig. 1 is a side elevation of an aeroplane door showing the handle mounted therein,

Fig. 2 is a sectional view of the door showing the handle in closed position,

Fig. 3 is a similar view showing the handle in open position,

Fig. 4 is a perspective view of the handle, and,

Fig. 5 is a perspective view of the link for connecting the handle to the latch operating rod.

In the drawing wherein for the purpose of illustration I have shown a preferred embodiment of my invention, the numeral 5 denotes the door of an aeroplane having the improved handle 6 applied thereto but it is to be understood the handle may be applied to the door of an automobile or any other similar closure. The handle 6 is of arcuate shape throughout its length and is adapted to fit within a longitudinal slot 7 formed in the surface of the door. A shank 8 projects from the concave face of the handle, adjacent one end, and is pivotally connected to one end of a link 9 by a pivot pin 10 which passes through apertures 11 in the end of the shank and an opening 12 in the end of the link. The pivot pin 10 is mounted on a bracket 13 fixedly attached to the inside of the door. A lug 14 extends longitudinally from the end of the shank 8 adapted to contact one side of the link 9 when the handle is in the position shown in Fig. 3. A spring 15 seated in a recess 16 in the side of the link 9 presses against the lug 14 and nor-

mally moves the handle to its concealed position shown in Fig. 2. The opposite end of the link 9 is bifurcated to receive the end of the latch operating rod 17 and has apertures 18 to receive a pivot pin 19 pivotally connecting the rod and link together. The rod 17 operates the latch bolt 20 of the latch mechanism 21. A lock may be built in the latch mechanism or the handle whichever may be preferred.

10 In operation, when the latch bolt is in closed position, the handle 6 automatically assumes the position shown in Fig. 2. In this position the entire handle is confined within the slot 7 of the door, both ends being disposed within the slot so they do not project beyond the door surface. 15 To open the latch pressure is applied to one end of the handle, as indicated by the arrow in Fig. 3, which rocks the handle to swing the opposite end outwardly from the slot beyond the door surface 20 so that it may be gripped by the hand. This initial movement of the handle does not move the link 9 but compresses the spring 15, allowing lug 14 to contact the side of the link. With lug 14 in contact with the link further movement of the handle in an outward direction will rock the link 9 and move the latch operating rod 17 to withdraw the latch bolt 20, thus opening the latch.

25 It is to be understood that the form of my invention herein shown and described is to be taken as a preferred example of the same and that certain changes in the shape, size and arrangement of the parts may be made without departing from the spirit of the invention or the scope of the subjoined claim.

30 Having thus described my invention, I claim:

35 A latch operating mechanism for a closure comprising a bracket mounted upon the inner side of the closure, a handle having a shank intermediate its ends, said shank being pivotally mounted on a pivot of the bracket and of a length to present the handle within a slot formed in the closure, a link having one end pivotally mounted upon the pivot of the bracket, the opposite end 40 of the link being bifurcated, a latch mechanism having an operating rod pivotally connected within the bifurcations of the link, the shank of the handle having a lug at its end for engaging one side of said link when the handle is moved 45 about said pivot to project one end of the handle from the slot, and a spring member interposed between said lug and link normally holding said handle with its ends confined within the slot, but compressible to allow said lug to engage said link and impart movement to said link and operating rod.
